LEG BONE BREAKER AND TENDON PULLER

Joseph Edward Jaeger, Los Angeles, Calif.

Application October 23, 1934, Serial No. 749,586

2 Claims. (Cl. 17—11)

In turkeys, and to some extent in other fowl, the upper part of the leg, or thigh, contains long flat bones in addition to the large central bone. These so-called "splinter-bones" extend through the flesh of the thigh, the lower ends of the said bones being attached to the lower leg or ankle by means of tendons or cords. Even after the fowl is cooked these flat bones are almost impossible to cut, and cause considerable difficulty in re-
5 moving the meat from the thigh.

The purpose of my invention is to provide a means whereby the lower leg may be broken at a point near the ankle, and also to provide a means whereby the foot and the lower broken 15 part of the lower leg, with the cords still attached thereto, may be drawn out of the thigh, bringing with them the flat bones; at the sametime holding the thigh and preventing it from deformation or other injury.

20 I accomplish these objects by means of the mechanism shown in the accompanying drawing in which: Figure 1 is a side elevation of the device. Figure 2 is a plan view of the device. Figure 3 is a perspective view of the device with the lower leg in position, ready to be broken. Figure 4 is a perspective view showing the lower leg after being broken and with the tendons pulled partly out. Figure 5 is a perspective view showing the device in its final position, with the tendons pulled entirely out of the leg. Figure 6 is a sectional view through the lever and frame taken on the line 6—6 of Figure 1. Similar numerals refer to similar parts in the several views.

The construction of my device is as follows: 35 **10** is a stationary frame provided with means for securing the device to the wall, such as the slots **11** which are suitable to be held in place by lag screws or other similar means. The device is preferably mounted on the wall in a vertical 40 position. Integral with the frame **10** and extending outwardly and perpendicularly therefrom is a rib **12**. At the upper end of the rib **12** is a jaw **14**, of the so-called "alligator" type. The upper and lower jaws **14** and **14a** are provided 45 with teeth **13** and **13a** which are adapted to hold the lower leg **15** of a fowl, at a point adjacent to the lower end of the thigh **16**; the opening between the said jaws **14** and **14a** being such as to admit the lower leg **15**, but preventing the passage of the thigh **16**. The jaws **14** and **14a** may be reinforced or ribbed as shown at **17** if desired. Secured to the rib **12** at its lower end is a bolt or pin **18**. Revolvably mounted on the bolt **18** is a lever arm **19**, the bolt-opening **20** therein be-

ing curved so as to permit a certain degree of lateral swing. Both the inner and outer faces of the said lever and boss **21** are also curved to permit such lateral swing. The amount of this lateral swing of the lever **19** is limited by the bracket **5** **22**, which is integral with or attached to the frame **10**. Integral with the lever **19** on its front side is a lug **23** similar in shape and location to the jaws **14** and **14a** but without teeth, and which can be brought into registry with the jaws **14** and **10** **14a** by the movement of the lever **19**.

The operation of my device is as follows: The device having been secured to a firm support, preferably in a vertical position on a wall, the lever **19** is rotated to a position adjacent to the **15** rib **12** and the jaws **14** and **14a**. The lower leg **15** of the fowl is placed in the fixed jaws **14** and **14a** and the lever jaw **23**, with the foot **24** projecting beyond the jaw **23** and with the knee joint and thigh **16** on the side of the jaws **14** and **14a** far-
20thest from the lever, the said lever being swung laterally against the bracket **22**, to give more leverage for the next movement of the lever. The lever **19** is then given a quick, downward jerk breaking the bone as shown in Figure 4. **25** By continuing the forward and downward rotation of the lever **19** the tendons are pulled entirely out of the leg, bringing with them the flat bones **25** as shown in Figure 5. In practice the body of the fowl is held in position by one hand while the lever **19** is operated by the other hand.
30

What I claim as my invention and desire to secure by Letters Patent is:—

1. In a machine of the class described, the combination of a stationary frame having jaws **35** adapted to hold the leg of a fowl, and a lever rotatably mounted on said frame, said lever having a similar jaw adapted to hold the lower portion of the leg and foot of the said fowl, said lever being so mounted as to permit a limited lateral **40** movement in addition to the rotative movement for the purpose shown and described.

2. In a machine of the class described, the combination of a stationary frame having jaws **45** adapted to hold the leg of a fowl, a lever rotatably mounted on said frame, and said lever having a similar jaw adapted to hold the lower portion of the leg and foot of the said fowl, said lever being so mounted as to permit a lateral movement in addition to the rotative movement, and a bracket on said frame to limit the said lateral movement, for the purpose shown and described.
